UNITED STATES PATENT OFFICE.

HENRIETTA F. DUKE, OF NEW YORK, N. Y., ASSIGNOR TO THE BUTTERICK PUBLISHING COMPANY, (LIMITED,) OF SAME PLACE.

DESIGN FOR A LADY'S COSTUME.

SPECIFICATION forming part of Design No. 18,245, dated April 10, 1888.

Application filed February 23, 1888. Serial No. 265,050. Term of patent 3½ years.

To all whom it may concern:

Be it known that I, HENRIETTA F. DUKE, of the city, county, and State of New York, have invented and produced a new and original 5 Design for a Pattern of a Lady's Costume; and I do hereby declare that the engraved prints accompanying this specification convey to any one accustomed to using paper patterns a clear understanding of how a garment made up by 10 the pattern will appear.

The design shows a basque and a round walking-skirt. The skirt displays a pointed pannier at the left side that exhibits draping plaits in its top; a long right-side drapery slanting from 15 the belt toward the center of the front gore, curving toward the lower edge below a group of upturning plaits, and falling in kilt plaits near the back edge and in jabot folds at the lower part of its front edge; a waterfall back 20 drapery falling in free folds to the edge of the skirt, and overhanging at the left side by a wing

drapery that displays a fullness in its upper edge and falls in jabot folds at its back edge. The basque displays close-fitting fronts reversed in lapels above the waist-line and closed 25 below the lapels, a vest that exhibits a closing at the center and extends a little below the fronts, a close-fitting back that shapes a 30 pannier which is open at the center and fancifully shaped out at its overlapping front edge, 35 a rolling collar meeting the lapels in notches, a high standing collar, and coat-sleeves.

What I claim as my invention, and desire to secure by Letters Patent, is—

The design for a lady's costume, as shown 35 in the engraved prints accompanying this specification.

HENRIETTA F. DUKE.
